UNITED STATES PATENT OFFICE

2,429,411

1-ALKOXY-2,4-PENTADIENES AND SUBSTITUTED DERIVATIVES THEREOF

Ewart Ray Herbert Jones, London, and John Talbot McCombie, Manchester, England, assignors to Imperial Chemical Industries Limited, a corporation of Great Britain

No Drawing. Application December 19, 1944, Serial No. 568,940. In Great Britain February 10, 1944

4 Claims. (Cl. 260—614)

1

This invention relates to a process for the manufacture of new unsaturated compounds and more particularly it relates to the manufacture of new compounds of the general formula

wherein R, R', R², R³ and R⁴ may be hydrogen or alkyl groups of not more than 6 carbon atoms, the same or different, R⁵ may be hydrogen, an alkyl group of not more than 4 carbon atoms, a vinyl, methylvinyl or dimethylvinyl group, and wherein X is a hydroxyl group, an alkoxy group or an acid radical, for example a halogen atom or the group —OCOAlkyl.

According to the invention we bring about the isomerisation of dienols of the formula

to give dienols of the formula

in both of which formulae R, R', R², R³, R⁴ and R⁵ have the significance given above, by a process which comprises subjecting the first mentioned dienols to the action of an acidic substance of the kind hereinafter described.

The starting-out materials of the formula given above may be obtained, when R⁴ is hydrogen, by the partial hydrogenation of unsaturated ethinylcarbinols of the formula

wherein R, R', R², R³ and R⁵ have the significance given above. Thus vinyllethinyllcarbinol

may be hydrogenated to give divinylcarbinol

and propenylethinyllcarbinol

may be hydrogenated to give propenylvinylcarbinol, $CH_3CH=CH.CH(OH).CH=CH_2$; similarly 2-methylpropenylethinyllcarbinol (or, as it may also be named, 5-methylhexen-4-in-1-ol-3), $(CH_3)_2C=CH.CH(OH).C\equiv CH$, gives rise to 2-methylpropenylvinylcarbinol (or, as it may also be named, 5-methylhexadien-1:4-ol-3),

4-ethylocten-4-in-1-ol-3

2

gives 4-ethyloctadien-1:4-ol-3

3-methylnonadien-2:7-in-4-ol-6

5 $CH_3CH=CH.CH(OH).C\equiv C.CMe=CHCH_3$

gives 3-methylnonatrien-2:4:7-ol-6

10 octadien-1:6-in-3-ol-5

gives octatrien-1:3:6-ol-5

15 2-methyloctadien-1:6-in-3-ol-5

gives 2-methyloctatrien-1:3:6-ol-5

20 $CH_3.CH=CH.CH(OH).CH=CH.CMe=CH_2$

2:7-dimethyloctadien-1:6-in-3-ol-5

gives 2:7-dimethyloctatrien-1:3:6-ol-5

25 $CH_3.CMe=CH.CH(OH).CH=CH.CMe=CH_2$

2-methyl-6-ethyldecadien-1:6-in-3-ol-5

30 gives 2-methyl-6-ethyl-decatrien-1:3:6-ol-5

6-ethyldecen-6-in-3-ol-5

35 gives 6-ethyldecadien-3:6-ol-5

and 3:5-dimethylhexen-4-in-1-ol-3

40 gives 3:5-dimethylhexadien-1:4-ol-3

45 All these and other products are suitable for use in the process of the invention. The unsaturated ethinylcarbinols, from which the above dienols used in the process of the invention are obtained by partial hydrogenation, may themselves be obtained by known methods, that is to say by condensation of an unsaturated aldehyde or ketone, for example acrolein, crotonaldehyde, 2-ethylhexen-2-al-1, 2-methylcrotonaldehyde, or mesityl oxide, with alkali metal acetylides derived from, for example acetylene, ethylacetylene, vinylacet-

55 ylene or 1:2-dimethylvinylacetylene, under suit-

able conditions, as is described for example in United States Patents Nos. 2,125,384, 2,106,180, 2,106,181, and 2,106,182.

Where R^4 is an alkyl radical the starting materials may not, of course be made by partial hydrogenation of an unsaturated ethinylcarbinol. However they can frequently be made by reduction of the corresponding ketone. Thus the dienol 2:6-dimethylheptadien-2:5-ol-4

may be made by reduction of phorone.

The acidic substances used in bringing about the isomerisation process of the invention are mineral acids for example boric acid, phosphoric acid, nitric acid, hydrochloric acid, and sulphuric acid, acid salts for example potassium hydrogen sulphate, and organic acids, for example formic acid, acetic acid and tartaric acid. Also esterifying derivatives of these mineral or organic acids may be used, for example their anhydrides, for example acetic anhydride.

The reaction, when using the acids themselves, may conveniently be carried out in aqueous medium. An aqueous solution of the acidic substance may be used, of, for example, 2.5-25% strength, weight per volume, but more dilute or even stronger solutions may be used. The process of the invention may conveniently be carried out for example by enclosing the dienol which it is desired to isomerise in a suitable vessel together with a substantial proportion of an aqueous solution of the acidic substance, the vessel being shaken or the contents stirred at, for example, atmospheric temperature, for a period which may vary from 3 to 100 hours or more or less according to the speed at which the reaction takes place. A solvent, for example ethanol, may be present if desired and this may be added in amount sufficient to afford a homogeneous solution, in which case agitation may be omitted. The speed of isomerisation varies according to the particular acidic substance being used and also according to the strength of the solution of the acidic substance being used when working in aqueous medium. The speed of isomerisation also varies according to the temperature at which isomerisation takes place and although isomerisation of some of these dienols takes place rapidly at room temperature in order to isomerize others rapidly it is advantageous to work at a higher temperature, for example at 100° C.

It is not however essential to carry out the isomerisation process in aqueous medium and when using functional derivatives of acids for example, as for instance acetic anhydride, it is of course desirable to avoid the presence of moisture. An anhydrous inert solvent may be used or a solvent may be dispensed with. Under these conditions the isomerised dienol is isolated in the form of its ester. Thus when using acetic anhydride it is isolated in the form of the acetate. Also when working in aqueous medium there is a tendency for the isomerised dienol to be partly or wholly converted to an ester by the isomerising acidic substance. Particularly is this the case when using certain acidic substances, for example hydrochloric acid. Esterification is favoured by high temperature and by high concentration of the acidic substance. Thus when using hydrochloric acid, if it is desired to avoid formation of the ester it is advisable to work with a dilute aqueous hydrochloric acid and at room temperature but using a stronger acid a good yield of ester may be obtained. When using

sulphuric acid on the other hand isomerisation is not accompanied by appreciable esterification unless very high concentrations of acid are used.

Alternatively again the isomerisation may be carried out by using as acidic substance, for example concentrated sulphuric acid, in solution in an alcoholic solvent, for example methanol, ethanol or ethylene chlorohydrin. Under these conditions it is found that isomerisation is frequently accompanied by etherification of the isomerised dienol in which case the product is isolated in the form of the ether.

The products obtained according to the invention are useful as intermediates in the manufacture of polymeric materials.

The invention is illustrated but not limited by the following examples in which parts, except where otherwise stated, are by weight:

20

Example 1

210 parts of propenylvinylcarbinol (hexadien-1:4-ol-3) are added to 550 parts of aqueous sulphuric acid (containing per 100 parts by volume 1 part of sulphuric acid) in a vessel in which the air is replaced by nitrogen. The vessel is then shaken during 2 hours at 15-20° C. The contents of the vessel are then thoroughly extracted with ether. The ethereal extract is washed with water and with an aqueous solution of sodium bicarbonate until free from acid. It is then dried and distilled. There is thus obtained a colourless liquid of B. P. 67-68° C./26 mms. and n_{D}^{19} 1.4810. This is butadienylmethylcarbinol (hexadien-1:3-ol-5). With α -naphthyl isocyanate it gives an α -naphthylurethane M. P. 86.5-87.5° C.

Example 2

30 parts of propenylvinylcarbinol are added slowly to a cold solution of 1 part of concentrated sulphuric acid in 81 parts of methanol. The mixture is allowed to stand at 20° C. during 4 days. 500 parts of water are then added and the mixture is extracted with ether. The ethereal extract is washed until free from acid, dried and distilled. There is thus obtained a colourless liquid of B. P. 61-62° C./100 mms. and n_{D}^{19} 1.4488. This is 5-methoxyhexadiene-1:3.

50

Example 3

50 parts of propenylvinylcarbinol and 55 parts of acetic anhydride are mixed together and heated in an atmosphere of nitrogen on a steam-bath during 2 hours. Water is then added and when the acetic anhydride is completely hydrolysed the mixture is extracted with ether. The ethereal extract is washed with water and with aqueous sodium bicarbonate until free from acid and is then distilled. There is obtained a colourless liquid of B. P. 63-66° C./20 mms., and $n_{D}^{18.0}$ 1.4583. This is 5-acetoxyhexadiene-1:3.

65

Example 4

116 parts of propenylvinylcarbinol are added slowly to a cold solution of 4 parts of concentrated sulphuric acid dissolved in 316 parts of absolute ethanol. The mixture is allowed to stand for 20 hours at room temperature. 1500 parts of water are then added and the mixture is extracted with ether. The ethereal extract is washed with water until free from acid, dried and distilled. There is thus obtained a colourless, mobile liquid of B. P. 62.0-62.5° C./77 mms. and n_{D}^{17} 1.4484. This is 5-ethoxyhexadien-1:3.

Example 5

A mixture of 6 parts of 3-methylhexadien-1:4-ol-3, 400 parts of aqueous sulphuric acid (containing per 100 parts by volume 0.5 part of sulphuric acid) and a trace of hydroquinone is agitated at 20° C. during 25 minutes in an atmospheric of nitrogen. The product is then isolated as is described in Example 1 and there is obtained 4-methylhexadien-3:5-ol-2, B. P. 73-75° C./14 mms., n_{D}^{20} c. 1.4878. This substance when treated with maleic anhydride in benzene solution gives an addition compound of M. P. 193-194° C.

Example 6

A mixture of 11.7 parts of divinylcarbinol and 100 parts of aqueous sulphuric acid (containing per 100 parts by volume 1 part of sulphuric acid) is agitated at 20° C. during 24 hours in an atmosphere of nitrogen. The product is then isolated by ethereal extraction as is described in Example 1 and is fractionally distilled. There is obtained a fraction after two distillations B. P. 95-97° C./100 mms., n_{D}^{18} c. 1.4902. This substance is pentadiene-2:4-ol-1. When reacted with α -naphthylisocyanate it gives an α -naphthylurethane M. P. 97.5° C. and with maleic anhydride it gives an addition product M. P. 175-176° C. When allowed to stand in air pentadiene-2:4-ol-1 changes slowly yielding a transparent polymeric substance.

Example 7

A mixture of 10 parts of isopropenylvinylcarbinol, 100 parts of aqueous sulphuric acid (containing per 100 parts by volume 2 parts of sulphuric acid) and a trace of hydroquinone is agitated at 20° C. during 24 hours in an atmosphere of nitrogen. Common salt is then added to the mixture until no more will dissolve. The product is then isolated by extraction with ether as is described in Example 1. There is obtained 2-methylpentadien-2:4-ol-1 as a colourless liquid B. P. 97-99° C./50 mms., 72°-74° C./15 mms., $n_{D}^{13.5}$ c. 1.5001. It gives with α -naphthylisocyanate an α -naphthylurethane M. P. 59-60° C. and with maleic anhydride an addition product M. P. 181-182° C.

Example 8

A mixture of 30 parts of propenylvinylcarbinol, 124 parts of ethylene chlorohydrin and 1 part of concentrated sulphuric acid is stored at atmospheric temperature during 2-5 days. The product is then isolated as described in Example 1 and there is obtained after fractional distillation, 2- β -chloroethoxyhexadien-3:5, B. P. 79.5° C./7.5 mms., $n_{D}^{22.5}$ c. 1.4910.

We claim:

1. Process of preparing unsaturated ethers of the general formula

wherein R stands for an alkyl group containing up to 6 carbon atoms, R^1 , R^2 , R^3 are each selected

from the group consisting of hydrogen and alkyl groups containing up to 6 carbon atoms, and R^4 is selected from the group consisting of hydrogen, the vinyl, methylvinyl and dimethylvinyl groups, which process comprises subjecting a compound of the general formula

in which R , R^1 , R^2 , R^3 and R^4 have the same meaning as above, to the action of a mineral acid dissolved in an alcoholic solvent.

2. Process of preparing unsaturated ethers of the general formula

15 wherein R stands for an alkyl group containing up to 6 carbon atoms, and R^1 , R^2 and R^3 are each selected from the group consisting of hydrogen and alkyl groups containing up to 6 carbon atoms, which process comprises subjecting a compound of the general formula

in which R^1 , R^2 and R^3 have the same meaning as above, to the action of concentrated sulfuric acid dissolved in an alcoholic solvent.

3. Unsaturated ethers of the general formula

30 wherein R stands for an alkyl group containing up to 6 carbon atoms, R^1 , R^2 and R^3 are each selected from the group consisting of hydrogen and alkyl groups containing up to 6 carbon atoms, and R^4 is selected from the group consisting of hydrogen, the vinyl, methylvinyl and dimethylvinyl groups.

4. Unsaturated ethers of the general formula

40 wherein R stands for an alkyl group containing up to 6 carbon atoms, and R^1 , R^2 and R^3 are each selected from the group consisting of hydrogen and alkyl groups containing up to 6 carbon atoms.

EWART RAY HERBERT JONES.
